UNITED STATES PATENT OFFICE.

RALPH N. BURBANK, OF SOMERSET, MASSACHUSETTS.

ANTISAGGING ADJUNCT FOR FLEXIBLE BEDS.

Application filed May 16, 1923. Serial No. 639,273.

To all whom it may concern:

Be it known that I, RALPH N. BURBANK, a citizen of the United States, residing at Somerset, in the county of Bristol and State 5 of Massachusetts, have invented new and useful Improvements in Antisagging Adjuncts for Flexible Beds, of which the following is a specification.

The object of the invention is to provide 10 means for readily making the flexible bottom or spring element of a berth, transom, bed, or couch, sufficiently firm or inflexible to enable it to be used as a seat without sagging under the weight of a person sitting 15 thereon, said means being adapted to be quickly and conveniently rendered operative to prevent sagging or downward flexure of the spring element, when the latter is to be used as a seat, and inoperative to permit 20 such flexure when the bed is to perform its ordinary function.

The invention is embodied in the improved adjunct hereinafter described and claimed.

25 Of the accompanying drawings showing my improved adjunct applied to a yacht,— Figure 1 is a side elevation showing an ordinary bed including a flexible bottom, a frame supporting the bottom, and a mattress supported by the bottom, and an anti-sagging adjunct embodying the invention, said adjunct being in its operative position.

Figure 2 is a plan view of the same, the bed bottom and mattress being removed.

35 Figure 3 is a section on line 3—3 of Figure 1.

Figure 4 is a view similar to Figure 1, showing the adjunct in its inoperative position.

40 Figure 5 is a section on line 5—5 of Figure 4.

Figure 6 is an enlargement of a portion of Figure 1.

Figure 7 is a view similar to Figure 3, 45 showing the adjunct provided with a cushion.

The same reference characters indicate the same parts in all the figures.

My improved adjunct may be used with 50 any suitable flexible bed, couch, etc., and, as here shown, is used with a bed comprising a spring wire bottom or spring element 12 of the "National" type, a frame supporting said bottom and composed of cross-bars 13, and side bars 14, and a mattress 15 supported by the bottom 12. The frame

supports the spring element horizontally above a receiving space.

In this instance the frame cross-bars rest on fixed supports 16, within the cabin of a 60 yacht, a portion of the hull of which is shown at 17, the cabin floor being shown at 18. The bed is located in a suitable berth structure, of which 19 is the front, and 20, 65 21 are the ends.

In carrying out my invention, I provide a bed of the general construction above described, or of any other suitable construction, with an anti-sagging adjunct comprising a movable practically inflexible platform 70 21, adapted to bear on the under side of the bed bottom or spring element 12, and supporting means adapted to hold said platform in an operative position contacting with the bed bottom, as shown by Figures 1 and 3, so 75 that downward flexure of the bottom is prevented.

The platform is movable to an inoperative position out of contact with the bed bottom, 80 as shown by Figures 4 and 5, so that downward flexure of the bed bottom is permitted. The platform may be made of one or more boards, its area being sufficient to enable it to contact with any desired area of the bed bottom. Preferably the width of the platform is somewhat less than the width of the bed bottom, as shown by Figure 3.

I prefer to embody the platform-supporting means in a plurality of crank-rods, each comprising two arms 22, having trunnions 90 23 journaled in fixed bearings 24 below the bed, and a neck 25, connecting the arms 22, and journaled in bearings 26 on the platform. In this instance, the bearings 24 are formed in the side bars 24^a of a supporting 95 frame which includes transverse spacing bars 24^b as shown by Figure 2.

The arms 22 are adapted to swing to substantially vertical positions operatively supporting the platform, as shown by Figure 1, and to substantially horizontal positions inoperatively supporting the platform, 100 as shown by Figure 4.

I provide locking means adapted to confine the platform in its operative position, 105 said means being preferably embodied in a lug 27, fixed to one of the arms 22, and a brace 28, pivoted at 29 to one of the frame bars 24^a. The brace is provided with a slot or opening 30, arranged to engage the lug 110 27 when the arm 22 is in a vertical position. The lug is provided with a stop flange 31,

arranged to prevent lateral displacement of the brace from the lug.

To permit the convenient movement or shifting of the platform to its operative and inoperative position, I provide a crank 32 having a torque-transmitting engagement with one of the trunnions 23. Said trunnion may have a squared portion or shank adapted to be engaged by a squared socket 5 in the hub portion of the crank 32. A quarter turn of the crank is sufficient to move the platform from either position to the other. The crank is preferably removable so that it may be stowed away when 10 not required.

The platform 21 may be provided with a cushion 33 (Figure 7), which constitutes the portion of the platform contacting with the bed bottom.

20 It is obvious that an adjunct embodying my invention may be applied to a bed or couch in any apartment, and may form an adjunct of a portable bed or couch. The platform 21, and the described means for 25 supporting the same, constitute a converting adjunct for use with any spring bed which includes a downwardly yielding spring element 12 and a frame horizontally supporting said element above a receiving space, 30 the adjunct being adapted to convert the entire bed into a practically unyielding seat. The said adjunct is formed to enter said space, and the supporting means is adapted to support the platform in a depressed position, 35 out of contact with the spring element, so that the latter is free to yield under the weight of a recumbent occupant, and to rigidly support the platform in a raised position, in contact with the spring element, 40 so that the bed is converted into an unyielding or non-sagging seat, adapted to support a sitting occupant or occupants.

I claim:

1. A converting adjunct for use with a 45 spring bed which includes a downwardly yielding spring element and a frame horizontally supporting said element above a receiving space; said adjunct being formed to enter said space, and comprising a practically inflexible platform, and supporting 50 means adapted to support the platform in a depressed position, out of contact with the spring element, so that the latter is free to yield, and adapted also to support the 55 platform rigidly in a raised position in contact with said element, so that the bed is converted into an unyielding seat.

2. A converting adjunct for use with a 60 spring bed which includes a downwardly yielding spring element and a frame horizontally supporting said element above a receiving space; said adjunct being formed to enter said space, and comprising a practically inflexible platform, supporting means 65 adapted to support the platform in a de-

pressed position, out of contact with the spring element, so that the latter is free to yield, and adapted also to support the platform rigidly in a raised position in contact with said element, so that the bed is 70 converted into an unyielding seat; and operating means associated with said supporting means for depressing and raising said platform.

3. A converting adjunct for use with a 75 spring bed which includes a downwardly yielding spring element and a frame horizontally supporting said element above a receiving space; said adjunct being formed to enter said space, and comprising a practically inflexible platform, supporting means adapted to support the platform in a depressed position, out of contact with the spring element, so that the latter is free to yield, and adapted also to support the platform rigidly in a raised position in contact with said element, so that the bed is converted into an unyielding seat, and locking 80 means adapted to render said adjunct immovable when the platform is in a raised 85 position.

4. A converting adjunct for use with a 90 spring bed which includes a downwardly yielding spring element and a frame horizontally supporting said element above a 95 receiving space; said adjunct being formed to enter said space, and comprising a practically inflexible platform, supporting means adapted to support the platform in a depressed position, out of contact with the 100 spring element, so that the latter is free to yield, and adapted also to support the platform rigidly in a raised position in contact with said element, so that the bed is converted into an unyielding seat, and locking 105 means including a swinging brace pivoted to a fixed element of said supporting means, and adapted to separably engage a movable part of said adjunct and render the same immovable when the platform is in a raised 110 position.

5. A converting adjunct for use with a 115 spring bed which includes a downwardly yielding spring element and a frame horizontally supporting said element above a receiving space; said adjunct being formed to enter said space, and comprising a practically inflexible platform, and supporting 120 means adapted to support the platform in a depressed position, out of contact with the spring element, so that the latter is free to yield, and adapted also to support the platform rigidly in a raised position in contact with said element, so that the bed is converted into an unyielding seat, said supporting 125 means including fixed bearings located in the lower portion of said space, a plurality of crank rods comprising arms journaled in said bearings and necks connecting said arms and journaled in bear- 130

ings on the platform, said arms being adapted to swing to substantially horizontal positions supporting the platform in a depressed position, and to upright positions rigidly supporting the platform in a raised position.

6. A converting adjunct for use with a spring bed which includes a downwardly yielding spring element and a frame horizontally supporting said element above a receiving space; said adjunct being formed to enter said space, and comprising a practically inflexible platform, and supporting means adapted to support the platform in a depressed position, out of contact with the spring element, so that the latter is free to yield, and adapted also to support the platform rigidly in a raised position in contact with said element, so that the bed is converted into an unyielding seat, said support-

ing means including fixed bearings located in the lower portion of said space, a plurality of crank rods comprising arms journaled in said bearings and necks connecting said arms and journaled in bearings on the platform, said arms being adapted to swing to substantially horizontal positions supporting the platform in a depressed position, and to upright positions rigidly supporting the platform in a raised position, one of said arms being provided with a lug, the said adjunct comprising also a swinging brace pivoted to a fixed element of said supporting means, and adapted to separably engage said lug when the arms are upright, and thereby render the adjunct immovable.

In testimony whereof I have affixed my signature.

RALPH N. BURBANK.
